United States Patent Office

Des. 174,651
Patented May 3, 1955

174,651

PLANT MARKER OR SIMILAR ARTICLE

Theodore Pratt, Bena, Va.

Application January 25, 1954, Serial No. 28,645

Term of patent 7 years

(Cl. D35—2)

Fig. 1

Fig. 2

Fig. 3

To all whom it may concern:

Be it known that I, Theodore Pratt, a citizen of the United States, residing at Bena, Virginia, have invented a new, original, and ornamental Design for a Plant Marker or Similar Article, of which the following is a specification, reference being had to the accompanying drawing, forming a part thereof.

Fig. 1 is a top plan view of a plant marker or similar article, showing my new design;

Fig. 2 is a front view;

Fig. 3 is an end view; and

Fig. 4 is an exploded perspective view, as shown.

I claim:

The ornamental design for a plant marker or similar article, as shown.
